UNITED STATES PATENT OFFICE

1,929,740

SLOT AND SLUG FOR CHECK CONTROLLED APPARATUS

Harry Goetz, Chicago, Ill., assignor to Yale Slot & Slug Company, Chicago, Ill., a corporation of Illinois

Application May 25, 1932. Serial No. 613,379

REISSUED

11 Claims. (Cl. 194—4)

This invention relates to slots and slugs for check controlled apparatus, such as telephone sub-station instruments, and is concerned particularly with an attachment for converting the apparatus from a coin controlled device into a slug controlled device to thereby prevent surreptitious operation of the device with false tokens.

Many coin controlled devices, such as the coin collectors of telephone sub-stations, are provided with chutes protected by a housing which contains a circular pocket opening into the front face of the housing and through which a coin is inserted flat and brought into registration with the coin chute. My invention relates primarily to the conversion of a coin chute housing of this type into a slug receiving housing by an attachment which may be secured to the existing coin housing without mutilating that housing.

In its preferred form my invention consists of an attachment containing a guide adapted to lay against the front face of the coin chute housing and containing pockets adapted to register with the circular coin receiving openings in the front of that housing. These pockets preferably have round bottoms, and register accurately with the coin receiving openings to guide slugs or tokens into the coin chute of the device. A plate is located upon the top surface of the housing and guide, this plate containing rectangular slots which are guarded by projections arranged in accordance with the particular code that is to be used upon the slugs chosen for the installation. The guard and plate are held upon the housing by a metallic cap shaped to be fitted tightly thereover and containing ears which are depressed into existing indentations or openings in the housing to thereby securely fix the attachment on the housing. This preferred arrangement permits converting an existing coin controlled mechanism into a slug controlled mechanism without mutilating the coin controlled device by drilling holes therein.

My invention is further advantageous in that it permits readily changing the code by which the coin slots are guarded, so that an entirely different set of slugs must be used to operate the device. This is accomplished by removing the cap of the attachment device and replacing the slotted plate with a similar plate which contains slots guarded in accordance with the new code. The slugs adapted to the old plate are replaced by slugs adapted to the new plate, and surreptitious operation of the device is prevented.

While my invention is of great utility in connection with coin controlled telephone sub-stations, and is described in connection with such devices, it is equally applicable to any coin controlled device to convert the same so as to compel customers to purchase a slug in order to operate the device.

My invention will be best understood by reference to the accompanying drawing, in which a preferred embodiment of it is shown by way of example, and in which:

Figure 1 is a front elevational view of the device of my invention attached to a coin collector;

Figure 2 is a plan view of the device shown in Figure 1;

Figure 3 is an end view of the device shown in Figures 1 and 2;

Figure 4 is a cross-sectional view taken along the line 4—4 of Figure 1, looking in the direction of the arrows;

Figure 5 is a perspective view of the guide;

Figure 6 is a perspective view of the guard plate; and

Figure 7 is a fragmentary plan view of a modified form of guard plate.

Referring now to the drawing in more detail, I have shown a portion of a coin collector such as is commonly used in telephone pay stations, comprising a box or housing 1, containing coin chute 2, which communicates with a coin collector housing 3 located upon the top face of the box 1. As will be seen in Figure 4, this coin collector housing contains three circular openings 5 leading inwardly from its front face and communicating with the coin chutes 2. The housing 3 is attached to the box 1 in any preferred manner such as by rivets 6.

To convert a coin collector of this type into a slug or token collector, I place a guide 7 over the front face of the housing 3. As will be seen in Figure 5 this guide contains pockets 8 which open into the top edge of the guide and are adapted to register with the coin receiving openings 5 in the collector. The outside configuration of the guide 7 conforms with the shape of the housing 3. The guide may conveniently be a die casting composed of an aluminum alloy or other suitable die casting material. The guide is preferably considerably thicker than the slugs which are to be used in the device.

I place a slotted plate 9 across the top surfaces of the housing 3 and guide 7. This plate, shown in detail in Figure 6, is preferably composed of steel, which may be hardened, and contains a plurality of slots 10, one for each of the openings 5 in the coin box. Ear-like projections 11 extend

into the slots 10 to adapt the slot for the reception of a grooved disc of particular dimension, and at the same time to prevent the insertion of discs or coins which are not grooved properly to register with these projections 11. Grooved discs of this kind are well known in the art, being disclosed in the Patent 1,115,661 issued to Henry Goetz, November 3, 1914. The ends of the plate 9 are tapered at 12 to more closely register the same with the outside surfaces of the coin housing.

Over the housing, guide, and plate, I place a cap 15 which is preferably a single piece metallic cap shaped to accurately fit thereover. The cap may be composed of brass plated to give it a neat appearance. The top surface of this cap is provided with a plurality of slots 16 spaced to register with the slots 10 in the plate 9. The lower edge of the housing 15 fits down accurately upon the flange-like portion of the housing 3, inside of the rivets 6 by which the housing is attached to the coin box.

Coin housings of the type shown are provided with circular openings 17 extending from the bottom portion of the coin receiving pockets 5 out through the back side of the housing. I make use of these openings to secure the cap 15 to the housing by ears 18 which are forced out of the back wall of the cap into the openings 17. The free ends of the ears 18 engage the periphery of these openings to securely lock the cap in place upon the housing. Locking the cap in place will lock the guide 7 and guard plate 9 upon the housing through the engagement of the walls of the cap with these members.

The front face of the cap 15 is perforated with circular openings 19 which coincide with the coin receiving opening 5 in the housing 3, but are of smaller diameter so that coins or tokens will not pass therethrough into the coin chutes. Frequently the back wall of the coin housing contains numbers indicating the coin that the particular opening is adapted to receive, and these numbers are visible through the perforations 19 in the cap. The front face of the cap preferably contains suitable directions stamped therein in the manner shown in Figure 1.

In the operation of the device a slug of the proper type is inserted in the slot 16 in the cap and turned therein until the grooves contained in it register with the projections 11, at which time the slug is free to pass through the slot into the pocket 8 in the guide 7. In Figure 2 I have illustrated the manner of registering the slug with these projections.

Ordinarily a slug dropped into the pockets 8, of its own accord will move through the opening 5 into the coin chute 2; however, if it becomes stuck it can be easily pushed into the coin chute by inserting a finger through the opening 19 in the cap. Once in registration with the coin chute 2 the token drops into the mechanism contained in box 1 without further control.

As shown in Figures 2 and 6 the guard plate 9 is provided with three slots all of which are guarded by projections 11. This embodiment is shown by way of example only. Frequently in telephone sub-stations it is desirable to have the slot indicated by the figure 5 in Figure 1 guarded to prevent the entrance of a nickel therein in order to compel the user of the sub-station to buy a slug for an ordinary telephone call. At the same time, slots designated by figures 10 and 25 in Figure 1 and adapted to receive dimes and quarters, respectively, may conveniently be unguarded to permit the entrance of coins therein.

This is accomplished by omitting the indentations 11 from the slots in plate 9 which register with these latter two coin chutes.

Telephone pay stations are frequently operated by false slugs with the result that considerable loss falls upon the storekeeper upon whose premises the pay station is located, since the storekeeper must account to the telephone company for each token in the coin box. To minimize such losses it is desirable to frequently change the code of the slugs used in a particular pay station, so that only the slugs sold over the counter will operate the device. This arrangement has been found to be effective. To this end a plurality of different plates 9 may be provided for insertion in the attachment of my invention. In Figure 7 I have shown a plate 9' containing a rectangular slot 10' in which the projections 21 extending into the slot 10' are arranged differently from the projections 11 shown in the plate 9 in Figure 6. A slug 22 having corresponding grooves is shown in the slot 10'.

In order to insert the plate 9' in the attachment device, ears 18 are bent back out of engagement with the openings 17 by a blunt tool 100 projected through openings 19 in the cap 15. Since the cap is preferably made of a relatively soft material such as brass, the ears may be bent a number of times without breaking. With the cap thus loosened, it may be removed and the plate 9 is thus made accessible. The new plate 9' is inserted and the cap replaced and locked by reinsertion of ears 18 in the openings 17.

The attachment device of my invention closely registers with the coin chute housing and therefore must be designed to fit the same. The specific details of construction herein described are shown by way of example only and it is within the teachings of my invention to vary these details, thereby to adapt the device to other specific coin chute housings.

What is claimed is:

1. In combination, a perforated coin receiving housing of the type into which coins are inserted flat and moved into engagement with coin chutes leading out of the housing, and attachment means for arranging the housing to receive grooved slugs moved edgewise through slots in the top of the attachment, said means being secured to the housing solely by a removable encasing casing having ears registered with existing openings in said housing.

2. In combination, a perforated coin receiving housing of the type into which coins are inserted flat and moved into engagement with coin chutes leading out of the housing, and attachment means for arranging the housing to receive grooved slugs moved edgewise through slots in the top of the attachment, said means being encased in a metallic cap held upon the housing by ears projected into existing openings in the housing.

3. In combination, a perforated coin receiving housing of the type into which coins are inserted flat and moved into engagement with coin chutes leading out of the housing, and attachment means for arranging the housing to receive grooved slugs moved edgewise through slots in the top of the attachment, said means including a hardened metallic plate containing slots guarded to receive only a particular kind of slugs, and a removable casing for securing said plate in alignment with said housing, said plate being interchangeable with another plate containing

- slots guarded to receive only a different kind of slugs.
4. In combination, a housing having a plurality of depressions in the front face thereof for the reception of slugs, a guide fitted over the front face of said housing and having pockets opening from the top thereof and registering with said depressions, a plate resting on the top edges of said housing and guide and containing guarded slots registering with said pockets, a cap fitted over said housing, guide, and plate, and means on said cap engaging said housing for holding said assembly together. 80
5. In combination, a housing having a plurality of depressions in the front face thereof for the reception of slugs, a guide fitted over the front face of said housing and having pockets opening from the top thereof and registering with said depressions, a plate resting on the top edges of said housing and guide and containing slots guarded to pass a definitely formed slug but no other slug, a cap fitted over said housing, guide and plate and containing slots through which slugs may be passed to said plate and circular openings through which slugs may be digitally passed from said pockets into said depressions, and ears turned out of said cap into engagement with said housing for holding said assembly together. 95
- 20 6. The combination with a perforated coin housing of the type having circular coin receiving pockets recessed into the front face thereof and communicating with chutes leading into the mechanism upon which the housing is mounted, 100
- 30 of a plate resting on the top of said housing and overhanging the front face thereof and containing guarded slots disposed in the overhanging portion of the same, a cap fitted over said housing and plate, ears turned out of the cap into the 105
- 35 perforations in the housing to hold the cap and plate thereon, and means in the cap for guiding slugs dropped through said guarded slots through said pockets into said chutes.
- 40 7. The combination with a perforated coin housing of the type having circular coin receiving pockets recessed into the front face thereof and communicating with chutes leading into the mechanism upon which the housing is mounted, 110
- 45 of an attachment for converting the coin receiving housing into a slug receiving housing into which grooved slugs are inserted through rectangular slots located in the top thereof, said attachment comprising, a hardened metal guard plate containing slots into which projections ex- 115
- 50 tend to guard the same against passing slugs not grooved to fit the particular plate, said plate being interchangeable with a plate of different code thereby to change the slugs that will operate the mechanism, and means for holding the plate on the housing including ears turned into the existing perforations in the housing. 120
- 55 8. The combination with a perforated coin housing of the type having circular coin receiv- 125
- 60
- 65
- 70
- 75
- ing pockets recessed into the front face thereof and communicating with chutes leading into the mechanism upon which the housing is mounted, of an attachment for converting the coin receiving housing into a slug receiving housing into which grooved slugs are inserted through rectangular slots located in the top thereof, said attachment comprising, a hardened metal guard plate containing slots into which projections extend to guard the same against passing slugs not grooved to fit the particular plate, said plate being interchangeable with a plate of different code thereby to change the slugs that will operate the mechanism, a cap fitted over said housing and plate, said cap containing small circular perforations which are disposed concentrically of said pockets, and containing slots registered with said guarded slots, and ears turned out of said cap into existing perforations in said housing to fasten the attachment thereon. 130
- 80 9. As an article of manufacture, an attachment for converting the coin receiving means of a vending machine into a grooved slug receiving means comprising, a guide plate laid alongside the coin receiving means and having pockets opening from the top surface thereof, a guard plate laid over the top surfaces of the receiving means and guide plate and containing guarded slots which register with said pockets, a cap formed to fit over the coin receiving means and 135
- 85 said plates and containing ears adapted to be bent into engagement with said coin receiving means to lock the attachment assembly thereon.
- 90 10. As an article of manufacture, an attachment for converting a coin controlled device having a coin receiving means into which coins are moved horizontally through circular openings in the front face thereof, into a slug controlled device into which slugs are moved edgewise through rectangular slots in the top face thereof comprising, a guide adapted to fit against the front face of the coin receiving means and containing pockets registering with said circular openings and opening into the top face of the guide, a hardened metallic plate resting upon the tops of 140
- 95 said receiving means and guide and containing guarded slots registering with said pockets, metallic cap fitted over said receiving means, guide and plate and containing rectangular slots registering with the slots in said plate, and ears turned out of said cap into engagement with said receiving means to lock the attachment upon the device. 145
- 100 11. An attachment for converting a coin-receiving housing into a slug-receiving housing, comprising a slotted bar member disposed outwardly of and above said coin-receiving housing, a guide disposed on the side of said housing below said bar member, a removable enclosing casing receiving said bar member and guide and fitting down over said housing, and means carried by 150
- 105 said casing for holding said attachment in aligned position upon said housing.
